UNITED STATES PATENT OFFICE.

NATHAN GRIER MOORE, OF PEORIA, ILLINOIS.

TYPE-WRITING MACHINE.

SPECIFICATION forming part of Letters Patent No. 358,469, dated March 1, 1887.

Application filed December 19, 1884. Serial No. 150,708. (No model.)

To all whom it may concern:

Be it known that I, NATHAN GRIER MOORE, of Peoria, in the county of Peoria, in the State of Illinois, have invented an Improved Type-
5 Writer; and I do hereby declare that the following is a full, clear, and exact description thereof, reference being had to the annexed drawings, making a part of this specification, in which like letters of reference refer to like
10 parts, and in which—

Figure 2 represents a plan view of the same; Fig. 1, a side elevation; Figs. 3, 4, 5, 6, 7, 8, 9, and 10, views of various details of the mechanism.

15 This invention is in the line of type-writers in which a longitudinally-progressive and laterally-oscillatory roller is adapted by such movements to press a sheet of paper wrapped thereon against types held in the periphery of
20 a disk, a lever serving not only to turn said disk and thereby bring the desired letter in juxtaposition to said roller, but also, by its downward impression, to oscillate said roller against the type or letter.

25 The object of this invention is the effecting of several improvements in such a type-writer, of which the following are the chief: First, simpler and more effective mechanism for longitudinally shifting the roller and its carriage; second, means for inking the types; and, third, 30 automatic arrangements for revolving the roller.

In the drawings, R is the roller for carrying the paper; C, the carriage supporting said roller and adapted to travel longitudinally. C' is a frame pivoted to said carriage and containing the bearings of said roller.

The types project radially from the type-disk D, which is adapted to be revolved in a horizontal plane by means of the lever L, pivoted at one end to the lug L', projecting from said disk and near its center, to the shaft S. The crown D' and the letter-circle D'', being necessarily fixed in position, are secured to or formed as
45 a part of the plate F', as shown in Fig. 9, which plate is supported by the frame F. The type-disk D, being made annular and having its inner diameter fit loosely about the crown D', rests upon the projecting edge of the plate F', and can be revolved thereupon, with said crown as a center. The shaft S is loosely held

to permit longitudinal movement, and connects at its lower end with an angle-iron, S², by which its vertical motion transmits through the connecting-rod S³ the required oscillation 55 to the frame C' and its contained roller R.

The crown D' is sharply serrated, and the projection P of the lever L is made terminally V-shaped, that, when said lever is pressed down over any particular letter, the sloping 60 sides of said projection and the serration thereat shall cause, when the projection reaches the bottom of the serration, the lever to be exactly over the letter, although at first it may not have been placed quite true. When the projection P is rigidly fastened to the lever, the slight movement which said contact of the serration and projection gives to the disk D, coming at the same time with the forward oscillation of the roller R, causes the impression of 65 the type against the paper to be somewhat blurred. To prevent this, I adapt the projection P to be vertically movable in the lever L, having it pressed downwardly by means of the spring P''. The neck P' of the projection P 70 is square, to prevent its turning in the lever, and a cross-pin keeps it from dropping out from its opening in the lever.

The frame C' is pivoted at C'' to the carriage C, and is provided with the buffers C³ to stop 75 the backward oscillation of the frame C' and its contained roller R. Said backward oscillation is given to the frame C' by the spiral spring S⁴ on the connecting-rod S³, between the bearing S⁴ and the collar S⁵. To receive a part 80 of the shock of the forward throw of the roller R as it comes against the types T, I have constructed the buffers B, adjustably secured at the ends of the arms B². In front of each buffer B is a spring, B', by which the force of the impact of said roller is broken. Said arms B² 85 are fastened to the under side of the supporting-plate F'.
90

The carriage C is adapted to move longitudinally upon the ways O O'. Eyes O'' O'', 95 projecting from one side of said carriage, hold the same to the way-rod O, and the other side of said carriage is supported by a small friction-roller, O', movable between the two way-bars O' O'. To pull the carriage C in one direction a strap, I, is fastened at one end to the carriage, and is at the other extremity wrapped
100

about the wheel J. The wheel J is revolved by means of a spring coiled therein, (not shown in the drawings,) the tension of which is adjusted by means of the ratchet-wheel J² and 5 the pawl J³. The key-stem J' enables the spring to be wound up. This wheel J is continually pulling the carriage C forward. To control this pull and cause the said carriage to progress only the width of a letter after each 10 printing-stroke, I have devised the following construction: A rack-bar, E, is secured to the carriage C by pivots or hinges E'. A spring-catch, E², keeps the rack-bar down in place. Beneath said rack-bar and meshing therewith 15 is a gear-wheel, G, fast on the shaft G'. Fast on the other end of said shaft is an escape-wheel, G². The anchor-escapement H, pivoted at its center to suitable supports projecting up from the base-plate or board W, prevents 20 said escape-wheel G from revolving. The pawl H³, pivoted in a slot in the shaft S, is pressed within said slot when said shaft is pushed downward. When, however, said shaft is raised, this pawl pushes against the upward 25 end of the anchor-escapement H, releases its other end from contact with the escape-wheel G², and permits said wheel to revolve for the space of one tooth. This distance is arranged 30 to be the required space between each two letters printed by the writer.

To give the space between each two words and wherever else desired, I supply a lever H², by which, on pressing upon the button H' thereof, the escapement H is made to release 35 the wheel G². With each distinct movement of said lever the wheel G² moves one tooth and the carriage C is shifted accordingly.

My device for inking each type just previously to the impact thereagainst of the paper-wrapped roller R, is as follows: The arm K², pivoted at K⁴, to a lug projecting from below the plate I' carries at its outer extremity a small inking-roller, K, held to said arm by slender springs K'. This arm K² is thrown 45 upwardly with each downward stroke of the lever L and the shaft S by the impact against the end K³ of said arm of the friction-roller K⁵, held by the collar K⁶ fast on said shaft S. With the downward stroke of the lever L this 50 arm K² is carried up, the inking-roller K passes up against the type, which has just been turned thereto, suitably inking it, and is held up above the disk D, while the roller R comes forward against said type. Then as the pressure 55 is removed from the lever L said roller returns and the arm K² falls, and the inking-roller K therewith, to its original position. If the weight of said arm is not sufficient to replace it quickly, I design to furnish a suitable 60 spring for aiding such movement.

In order to return the carriage to begin another line, the spring-catch E² is released from the rack-bar E, and the same is raised up out of mesh with the gear-wheel G. The carriage 65 C can then be pushed back to its initial position without hinderance. When thus replaced, the rack-bar E is lowered to again mesh with

the gear-wheel G, the spring-catch E² re-engages with the said bar, and the carriage is all ready for its new line. Before beginning the 70 new line it is necessary, however, to turn the roller R a distance equal to the desired space between the lines. To do this automatically I have devised the following device:

The lever M, pivoted to the axis of the 75 roller R, has a pawl, M', engaging with the ratchet-wheel R' of said roller. Held in bearings N'', projecting from the way-bars O', is a triangular plate, N. A spring, N', pressing against the lug N³ of said triangular plate, 80 serves to keep the same in the position shown in Fig. 2. When the lever M travels along with the carriage in the working-passage, said plate N is simply pushed out of the way by the end of said lever; but when the carriage 85 is returned to begin a new line the lever M slides up on the sloping edge of the plate N, is raised, and the pawl of the lever M caused to engage with a new notch in the ratchet-wheel R'. As the pawl passes the plate N and drops down beyond the same, being pulled by the 90 spring M', the roller R is given the desired lineal change. In place of said plate N, I sometimes use the modification thereof shown in Fig. 7.

Instead of swinging horizontally, my new plate N¹⁰ is adapted by the horizontal axis N¹² to swing in a vertical plane parallel with the roller R. The lower half of this plate N¹⁰, being weighted at N¹³, as the paper-roller R is returned for a new line, the lever M comes in contact with the edge thereof, and is of course raised in order to pass it. This raising of the lever M, as previously described, enables its pawl to engage with a new ratchet-tooth of 100 the ratchet-wheel R'. To enable the spring M' to give a quick pull to said lever, and thereby a partial turn of the roller, the plate N¹⁰ has a quadrant cut therefrom at N¹⁴, which cut also enables the said plate to be revolved 110 by the lever when traveling in the opposite direction and to release said lever without raising the same.

At the end of the lever L, opposite to the presser-button L', is the finger L³, extending 115 through a slot in the lug L'', and terminating just over the edge of the type-disk D. The object of this finger is to enable the types to be adjusted relative to the crown and letter-circle. If, when the projection P is pressed into a 120 serration of the crown D', a type is not exactly beneath the end of said finger, it is at once evident that a correction is needed. To permit of this adjustment, the type disk D is composed of three thin annular disks, D³, D³, and D⁴. D³ are the outer disks, to the upper of 125 which the lug L'' is rigidly attached, while D⁴, the inner disk, is the type-disk proper. Said disk D⁴, I usually form of wood or hard rubber and divide its periphery into the radial notches D⁵, equal in number to the characters which I design the type-writer to have. By employing a suitable number of screws, D⁶, to clamp together these disks D³, D³, and D⁴, 130

and having the screw-holes in the disk D^4 elongated at right angles to the radii thereat, the said disk D^4 can be evidently revolved somewhat relatively to the disks D^3 , and hence 5 adjusted relative to the lever L and to the letter-circle. Figs. 8 and 9 show this arrangement of the type-disk. The disk D^4 , I make slightly thinner than the types, so that the disks D^3 can grip the types sufficiently hard to hold them securely in place.

I am aware that prior to my invention type-writers have been constructed in which are many of the details shown in the drawings and described in the specification of this application; hence I do not claim them broadly; 15 but

What I claim as my invention, and for which I desire Letters Patent, is as follows, to wit:

1. In a type-writer of the kind in which the 20 letter-circle is provided with a serrated crown and the actuating-lever with an elastic guide-pin by means of which said lever can be more accurately depressed over a desired letter, the combination, with the type-disk, the serrated 25 crown, and the actuating-lever, of the V-shaped projection or guide-pin P , having its neck easily movable in an aperture in said lever, the pin P' , for preventing withdrawal of said neck from said aperture, and the spring P'' , 30 fixed to said lever and adapted to depress said guide-pin, substantially as and for the purpose set forth.

2. In a type-writer, the combination, with the type-disk and the shaft S , of the lug L'' , 35 projecting rigidly from said type-disk, and the actuating-lever L , pivoted to said shaft and at one end to said lug and having said pivotal end prolonged to the periphery of said type-disk, substantially as and for the purpose set 40 forth.

3. In a type-writer, the plate D^4 , having the notches therein for receiving the types, in combination with the plates D^3 D^3 , adapted to clamp between them said plate D^4 and the 45 types, substantially as described.

4. In a type-writer, the disk-supporting plate F' , having the shaft S movable therein, the three annular disks D^3 , D^4 , and D^5 , clamped together by suitable screws and adapted to be 50 supported by said plate F' , said disk D^4 having the radial notches D^6 for receiving the types and having its screw-holes for said screws tangentially elongated, in combination with the lug L'' , projecting rigidly from the upper 55 of said disks D^3 , and the actuating-lever L , pivoted to said lug and to said shaft and having the finger L^3 , for the purposes specified.

5. In a disk type-writer, the combination, 60 with the type-disk D , the supporting-plate F' therefor, and the shaft S , of the arm K^2 , having the curved foot K^3 and pivoted near said foot to said plate, the collar fast on said shaft

and having a friction-roller, the springs K' , fixed to the free end of said arm, and the inking-roller K , supported at the ends of said 55 springs, substantially as and for the purpose set forth.

6. In a type-writer, the combination, with the type-disk D and the shaft S , of the arm K^2 , having suitable fulcrum-pivot and adapted to 70 be oscillated by the depression of said shaft, and the inking-roller K , elastically held at the free end of said arm, as set forth.

7. In a type-writer, the combination, with the paper-carrying roller adapted to be oscillated against the types, of the buffers B , rigidly supported and provided with the springs B' , 75 for receiving the impact of said roller, as and for the purpose set forth.

8. In a type-writer, the combination, with 80 the paper-roller, the type-disk, and the supporting-plate for said disk, of the arms B^2 , projecting rigidly from said plate, the buffers B , adjustably secured to the ends of said arms, and the springs B' , fixed to said buffers for receiving the impact of said roller, substantially 85 as specified.

9. In a type-writer, the combination, with the shaft S , adapted to be vertically moved, the escape-wheel G'' , controlling the paper-carriage by intermediate mechanism, substantially 90 as described, and the anchor-escapement H , engaging with said escape-wheel, of the pawl H^3 , pivotally held by the said shaft S and adapted to operate said anchor-escapement 95 when said shaft rises, as set forth.

10. In a type-writer, the combination, with the paper-carriage, the escape-wheel G'' , connected, substantially as described, with the carriage to permit the longitudinal movement 100 thereof, and the anchor-escapement H , controlling the rotation of said escape-wheel, of the lever H^2 , having a press-button, H' , and pivotal bearings, and the spring for elevating the said lever, the same being adapted to 105 actuate said escapement, as set forth.

11. In a type-writer, the combination, with the paper roller and carriage moving upon longitudinal ways, the ratchet-wheel fixed to an end of said roller, the lever pivoted to said 110 roller's bearing-axis beside said ratchet-wheel, the pawl for engaging said lever with said ratchet-wheel, and the spring for depressing said lever, of the plate N , having pivotal bearings in line with its vertical edge, and a spring 115 for pressing its free vertex toward said roller, as set forth.

In testimony that I claim the foregoing invention I have hereunto set my hand this 3d day of December, 1884.

NATHAN GRIER MOORE.
